UNITED STATES PATENT OFFICE

2,502,108

MOBILE CRANE

William Taylor, Salford, England

Application July 16, 1946, Serial No. 683,856
In Great Britain September 1, 1945

3 Claims. (Cl. 212—8)

1

This invention relates to improvements in mobile cranes such as are carried by self-propelled motor vehicles.

According to the invention the main jib of a crane is fulcrumed at its rear end on a frame carried by the chassis or other part of the vehicle, and supported at a point intermediate its ends on an auxiliary jib also fulcrumed on the frame a ram operating in an hydraulic cylinder raising or lowering the auxiliary jib which raises or lowers the main jib.

The invention is illustrated diagrammatically in and will be described with reference to the accompanying drawings in which:

Fig. 1 is a side elevation showing the jib in its lowest position;

Fig. 2 is a side elevation showing the jib in its highest position;

Fig. 3 shows a part side elevation of a modification of the mounting of the auxiliary jib on the main jib;

Fig. 4 is a section on line 4—4 Fig. 3 enlarged.

The main jib A¹ is fulcrumed at its rear end on a frame B¹ carried by the chassis at the rear end of the vehicle. The lower end of an auxiliary jib A² is pivoted on the frame B¹ adjacent to the chassis, the fulcrumed end of the two jibs A¹, A² being substantially separated with the upper end of the auxiliary jib A² connected to the main jib intermediate its ends by rollers a engaging runways or guides a¹ in the main jib A¹.

In the modification shown in Figs. 3 and 4 the main jib A¹ is provided with an inclined surface a² of channel shape on its underside the flanges a³ of which are engaged by flanged rollers a⁴ mounted on a shaft a⁵ carried by the auxiliary jib A² to enable a greater lift to be obtained or alternatively the same lift with less movement of the auxiliary jib whilst still allowing the main jib to be brought down to the position shown in Fig. 1.

The hook end of the main jib A¹ may be formed with a series of slots g to enable a hook G to be suspended at varying distances from the end.

The auxiliary jib A² is connected at a point intermediate its ends to two rams E working in two hydraulic cylinders E¹ pivoted on the members C¹ extending transversely of the chassis of the vehicle intermediate the front and rear wheels. The cylinders E¹ are mounted one at each side of the vehicle with the rams E pivoted on the auxiliary jib A².

I claim:

1. A mobile crane carried by a self-propelled motor vehicle comprising in combination a

chassis; a frame mounted on said chassis; a main jib pivoted at its rear end to said frame; an auxiliary jib pivoted to said frame at a point spaced from and below the pivoting point of said main jib; rollers on the free end of said auxiliary jib; flanges forming an inclined surface on the lower face of said main jib; arranged so as to be engaged by said rollers on said auxiliary jib; a hydraulic cylinder member; a motor member operating in said hydraulic cylinder member; first pivoting means pivoting one of said members to said chassis; and second pivoting means pivoting the other of said members to said auxiliary jib whereby movement of said motor member within said hydraulic cylinder member will raise or lower said auxiliary jib and thereby raise or lower said main jib too, said inclined surface giving increased lift to said main jib over that imparted by said motor.

2. A mobile crane carried by a movable vehicle comprising in combination a main jib; first pivoting means pivoting said main jib at its rear end to said movable vehicle; an auxiliary jib; second pivoting means pivoting said auxiliary jib at one end to said movable vehicle at a point spaced from and below said first pivoting means in such a manner that the other end of said auxiliary jib engages the lower face of said main jib at a point substantially spaced from said first pivoting means; a hydraulic cylinder member; a piston member operating in said hydraulic cylinder member; third pivoting means pivoting one of said members to said movable vehicle at a point spaced from said first and said second pivoting means; and fourth pivoting means pivoting the other of said members to said auxiliary jib at a point spaced from said second pivoting means whereby movement of said piston member within said hydraulic cylinder member will turn said auxiliary jib about said second pivoting means, which turning movement of said auxiliary jib in turn will result in turning of said main jib about said first pivoting means.

3. A mobile crane carried by a movable vehicle comprising in combination a main jib; first pivoting means pivoting said main jib at its rear end to said movable vehicle; an auxiliary jib; pivoted at its rear end to said vehicle at a point spaced from and below said first pivoting means; roller means freely rotatably mounted on the other end of said auxiliary jib; means forming a supporting surface on the lower face of said main jib arranged at a point spaced substantially from said first pivoting means in such a manner as to be engaged by said roller means; a hydraulic

cylinder member; a piston member operating in said hydraulic cylinder member; third pivoting means pivoting one of said members to said movable vehicle at a point spaced from said first and said second pivoting means; and fourth pivoting means pivoting the other of said members to said auxiliary jib at a point spaced from said second pivoting means whereby movement of said piston member within said hydraulic cylinder member will turn said auxiliary jib about said second pivoting means, which turning movement of said auxiliary jib in turn will result in turning of said main jib about said first pivoting means.
